UNITED STATES PATENT OFFICE.

ERNEST ADOLPH JAHN, OF LONDON, ENGLAND.

ATOMIZER OR PUMP-SPRAYER.

No. 842,097.

Specification of Letters Patent.

Patented Jan. 22, 1907.

Application filed July 16, 1906. Serial No. 326,501.

To all whom it may concern:

Be it known that I, ERNEST ADOLPH JAHN, a subject of the King of England, of the firm of Thomas Christy and Company, residing at 5 4, 10, and 12 Old Swan Lane, Upper Thames street, in the city of London, England, have invented new and useful Improvements in or Relating to Atomizers or Pump - Sprayers, of which the following is a specification.

My invention relates to improvements in atomizers or pump-sprayers for use for spraying scent and the like. The pump is of the well-known type wherein a piston controlled by a spring works in a cylinder, the upper part of which is attached to or formed with a metal body or chamber, this body or chamber being fitted into a receptacle of glass or other suitable material.

With sprays of the kind as hitherto constructed the cylinder is fitted at the bottom with a valve to prevent the air or perfume flowing back into the cylinder when the piston is raised for a fresh stroke. This valve is protected by a small hollow cap which is screwed onto the cylinder and provided with a hole in the center to allow the air to pass into the receptacle, or in some cases the air-outlet valve is dispensed with and an outlet-passage is provided sufficiently small to prevent any serious sucking back of the air through this outlet. A small tube, of metal or other suitable material, is attached to the outside of the cylinder and passes through the metal body and is connected at the top with a nozzle screwed or fitted onto the outside of the body, so that when the piston is pressed down and sufficient pressure is produced on the surface of the liquid the same is forced up through the aforesaid small tube 40 and issues from the nozzle in the form of a spray. To prevent leakage, the point of the nozzle is provided with a screw-cap.

Various defects have been noticed in pump-sprays constructed as described. For instance, the valve-hole in the before-mentioned cap has proved unsatisfactory, as a certain amount of liquid has invariably made its way through the valve, or the tube which takes the place of the air-outlet valve from the cylinder has been liable to be bent or damaged, and the screw-cap on the point of the nozzle does not always effect the purpose for which it is provided, as a certain quantity of perfume often escapes and runs down onto the 55 table.

My invention is designed to obviate these drawbacks. I first of all do away with the hole in the center of the cap and provide a passage in the wall of the cylinder opening out into the air-space and so giving the air free outlet from the cylinder-valve though preventing the liquid in the receptacle reaching the valve. To prevent leakage of the nozzle, I alter its construction as follows: In the ordinary form of pump-spray the top of the piston-rod is fitted with a circular top plate which when the piston is pushed down fits into the metal body of the pump. The piston-rod being provided to within about one-eighth of an inch of the top plate with two vertical guides fitting into the cylinder-cover enables the pump to be locked by a slight turn of the said top plate. This top plate I replace by a flanged hood fitting over the top of the spray. The flange may be provided with an opening and slot fitting over the nozzle, which in my invention is put back to about one-eighth of an inch from the outer diameter of the spray or pump. The slot is so arranged that besides covering the nozzle (so as to prevent its tearing the linings of dressing-bags, &c.) it also closes the hole in the nozzle and renders it air-tight, thus preventing all chance of leakage. The closing can be effected by lining the slot with a soft metal or any other suitable material, making same slightly eccentric to insure a lasting fit, and in order that this invention may be better understood I will now proceed to describe the same with reference to the drawings accompanying this specification, in which—

Figure 1 is an elevation of a pump-spray made according to my invention with the hood or cover closed. Fig. 2 is an elevation of same with the hood or cover open. Fig. 3 is a vertical section in a plane passing through the small delivery-tube with the hood closed. Fig. 4 is a vertical section in a plane at right angles to the plane of section in Fig. 3 with the hood open.

The same letters of reference are employed to denote the same parts in all the views.

The pump-spray is in general construction of a well-known type, and consequently it is unnecessary to go into minute details of such construction.

a is the receptacle, of glass or other suitable material, provided with a collar *b*, onto which the body *c* screws in the ordinary way, *11c*

a suitable washer *d* being interposed to make a liquid-tight joint. The body *c* has attached to or formed therewith a cylinder *e*, forming the cylinder of the pump. This 5 pump is of the ordinary construction in pump-sprays of the kind.

f is the piston, in which is the usual piston-valve.

g is a helical spring resting on the seating 10 *h*, which is provided with a hole *j*, furnished with the usual valve.

k is the small tube leading from the liquid 15 in the receptacle *a* to the nozzle.

It will be seen that the body *c* is so formed 20 that there is an annular chamber *m* around the cylinder *e*. This chamber is provided with a number of holes *n*, which open from it into the receptacle *a*. The top *o* of the pipe *k* passes into the nozzle *p* in such a way that 25 air can find its way from the chamber *m* and be supplied around the end *o* of the said tube *k* as the scent is delivered.

Referring now to the details of construction 30 which constitute the features of my present invention, in place of the valve-hole at the bottom of the cylinder or in place of the capillary tube leading to the chamber *m* found in some pump-sprays I close the cylinder at the bottom by a disk *r*, so that there is no possibility of liquid entering, and from the 35 lower chamber *s* thus formed at the bottom of the cylinder *e* I provide a passage *t* in the wall of the cylinder *e*, which communicates with the annular chamber *m*, as will be seen clearly in Fig. 4. When the pump is operated, the air driven therefrom passes into the chamber *s* and up the passage *t* into the chamber *m*, whence it escapes through the various holes *n*, and a pressure is produced 40 on the top of the liquid in the receptacle *a*. Consequently the liquid is forced up the tube *k* and delivered through the orifice *o* at the same time a portion of the compressed air finds its way around the aperture *m* and mixing 45 with the scent from the orifice at *o* the scent is delivered in the form of a fine spray from the nozzle *p*.

In place of the top plate I provide a flanged 50 hood *v*, the flange of which is provided with an opening and slot *u*. It will be seen that when the hood *u* is pushed down the slot comes over the nozzle *p*, and when the hood is rotated the nozzle is closely covered by the slot, which may be provided with soft metal 55 or other suitable material to keep it tight. The guides *w*, which when the cap is rotated take under the plate *z* assist in keeping the hood *v* locked.

In some cases I may place the nozzle *p* below 60 the flange of the hood when closed, where it is not desired to use the hood for the purpose of covering the nozzle, and I may in that case rely solely on the guides for keeping the hood closed, or I may provide suitable bosses taking into one or more open-

ings or slots in the flanged hood for the purpose of keeping same closed.

It is obvious that, if desired, more than one passage *t* can be provided in the walls of the cylinder *e*.

What I claim, and desire to secure by Letters Patent of the United States of America, is—

1. An atomizer or pump-spray comprising a pump of ordinary construction the lower 75 end of the cylinder of which opens into a chamber closed at the bottom, such chamber communicating by means of a passage or 80 passages in the wall of the cylinder with an annular chamber around the said cylinder which in turn communicates by suitable apertures 85 with the receptacle containing the scent to be sprayed, and also when desired with the nozzle of the pump all for the purposes set forth.

2. The combination with an atomizer or pump-spray of a flanged hood attached to the top of the piston or plunger rod, such hood being preferably so formed as to cover and lock over the nozzle of the pump when 90 the hood is in the closed position for the purposes set forth.

3. In an atomizer or pump-spray, the combination with the cylinder, of a plunger operating therein, an apertured plate arranged at the upper end of said cylinder and forming a guide for said plunger, a flanged hood attached to the top of said plunger, locking means carried by said cap and locking means carried by said plunger, substantially 100 as described.

4. In an atomizer or pump-spray, the combination with the cylinder, of a plunger operating therein, an apertured plate arranged at the upper end of said cylinder and forming a guide for said plunger, a flanged hood attached to the top of said plunger, a fluid-discharge tube, a nozzle arranged at the discharge end of said tube, said hood being provided with a recessed portion adapted to be thrust over and to lock upon said nozzle, substantially as described.

5. In an atomizer or pump-spray, the combination with the cylinder, of a plunger operating therein, an apertured plate arranged at the upper end of said cylinder and forming a guide for said plunger, a flanged hood attached to the top of said plunger, a fluid-discharge tube, a nozzle arranged at the discharge end of said tube, said hood being provided with a recessed portion adapted to be thrust over and to lock said nozzle, and locking means carried by said plunger, substantially as described.

6. In an atomizer or pump-spray, the combination with the cylinder, of a plunger operating therein, said cylinder opening into a closed chamber at the lower end thereof, an annular air-chamber formed around the upper end of said cylinder, air-passages leading 130

from said air-chamber to the liquid-container, an air-duct formed in the wall of said cylinder and communicating between said closed chamber and said air-chamber, a fluid-discharge pipe having its discharge end located in said air-chamber, a nozzle formed on said discharge end, a flanged hood attached to the upper end of said plunger, said hood being provided with a recessed portion

adapted to be thrust over said nozzle and locked thereon, substantially as described.

In testimony whereof I affix my signature in presence of two witnesses.

ERNEST ADOLPH JAHN.
